United States Patent Office

Des. 183,417

Patented Aug. 26, 1958

183,417

CHAIR

Morton R. Cohen, Chicago, Ill.

Application February 12, 1958, Serial No. 49,612

Term of patent 14 years

(Cl. D15—1)

Fig. 1 is a perspective view of a chair showing my new design;

Fig. 2 is a front elevational view of the same;

Fig. 3 is a side elevational view of the same; and

Fig. 4 is a front perspective view of the chair with the seat and backrest removed for convenience of illustration.

I claim:

The ornamental design for a chair, substantially as shown.
